UNITED STATES PATENT OFFICE.

FRANKLIN S. MCKENNEY, OF DETROIT, MICHIGAN, ASSIGNOR OF ONE-HALF
TO J. M. LONGYEAR, OF MARQUETTE, MICHIGAN.

DESIGN FOR A SETTING-DIE.

SPECIFICATION forming part of Design No. 26,077, dated September 22, 1896.

Application filed December 9, 1895. Serial No. 571,597. Term of patent 14 years.

To all whom it may concern:

Be it known that I, FRANKLIN S. MCKENNEY, a citizen of the United States, residing at Detroit, county of Wayne, State of Michigan, have invented and produced a new and original Design for a Setting-Die; and I declare the following to be a full, clear, and exact description of the same, reference being had to the accompanying drawings, which form a part of this specification.

In the drawings, Figure 1 is a view in perspective. Fig. 2 is a view partly in cross-section and partly in elevation. Fig. 3 is a plan view of the die-face.

The leading feature of my design consists of the conformation of the setting-die face,

said face being formed with two elongated cavities a' a^2 on opposite sides of the face, toward the outer edge thereof, separated by an intervening or middle portion a of the die-face. The two cavities a' a^2 of the die-face are of oblong and substantially of oval form, the elongated cavities being also concaved.

What I claim is—

The design for a setting-die herein shown and described.

In testimony whereof I sign this specification in the presence of two witnesses.

FRANKLIN S. MCKENNEY.

Witnesses:

N. S. WRIGHT,
M. A. MARTIN.
